UNITED STATES PATENT OFFICE.

MAX H. SEEGER, OF INGLEWOOD, CALIFORNIA.

HAIR CLEANER.

Application filed May 28, 1927. Serial No. 195,025.

This invention relates to a hair cleaner and method of making it, and an object thereof is to provide a sanitary means for removing dandruff, dust and impurities from the hair.

The hair cleaner can be embodied in a comb, brush and like appliance, and includes fibrous cleaners that are connected to the comb and brush in such a way that they thoroughly cleanse the hair when it is combed or brushed.

Another object of the invention is to provide a hair cleaner that is so simple to manufacture that it can be sold so cheaply that it can be discarded after it has once been used. That is each hair cleaner can be thrown away after it is once used, thereby being of great usefulness for sanitary purposes.

In other words hair dressers and barbers can use a hair cleaner on a customer and then throw it away so as not to infect another customer following, in the event disease was present in the hair of the one preceding. As is well known, many diseases of the hair and scalp are transmitted from person to person by use of the same comb and brush, and an object of the invention is to provide a simple and efficient means to prevent such diseases from being so transferred by providing combs and brushes that are so cheap that they can be thrown away once they are used.

An object of the invention is to provide cheap discardable combs and brushes for hospitals and the like where contagious diseases, such as scarlet fever, smallpox and leprosy are prevalent, whereby the appliances can be destroyed after they are once used.

A feature of the invention is shown in the construction of the teeth of the hair cleaner whereby they are provided with a plurality of small fibrous brushes extending at right angles to the strands of the teeth.

Other objects, advantages and features of invention may appear from the accompanying drawing, the subjoined detailed description and the appended claims.

The accompanying drawings illustrate the invention.

Figure 1 is a fragmental view of a twisted strand from which the teeth of a hair cleaner is formed.

Fig. 2 is a side view of a sanitary hair cleaner constructed in accordance with this

invention in the form of a comb with the teeth shown semi-diagrammatically; that is, a single line indicates the two wires twisted into a strand.

Fig. 3 is an enlarged cross section on the line 3-3 of Fig. 2.

Fig. 4 is a fragmental longitudinal section on line 4-4, Fig. 3.

Fig. 5 is a longitudinal section through a sanitary hair cleaner in the form of a brush, with the teeth shown semidiagrammatically.

Fig. 6 is a cross section on line 6-6, Fig. 5, also showing the teeth semidiagrammatically.

The method of forming the sanitary hair cleaner consists in twisting two wires 10 and 11 together and simultaneously throwing a cotton or other fibrous thread backward and forward between the twisting wires and cutting the thread so as to leave short lengths of string 12 between each of the twists that are held at right angle to the twisted strands. Then causing the extended ends of the fibrous strings 12 to unravel and become fuzzy, to thereby form a plurality of small cleansing brushes on the teeth of the hair cleaner. Then bending the strand so as to form integrally connected V-shaped teeth 13 that extend throughout the length of a comb when so used; or the full length of a brush backing when used in a brush. After the teeth are formed the butt ends are extended into a channel of a metal backing of a comb 14 that has its sides 15, 16 pressed firmly and securely to the teeth; or if used with a brush several rows of the integral teeth are secured in parallel channels 17 in the brush backing 18.

It is understood that the strand formed of the wires 10 and 11 and cross thread 12 can be of any length. That is spools of several thousand feet can be wound and woven together, it being understood that mechanism is provided for so forming the strands and for bending the formed strands into teeth and severing proper lengths of integrally connected teeth to fit into combs or brush backings.

It is also understood that the wire strand is of sufficient strength to resist bending when in use.

As thus formed the hair cleaner in the form of a sanitary brush or comb is used substantially as is an ordinary brush or comb, and when so used the numerous small fibrous brushes cleanse the hair of dandruff,

dust and impurities, and when once used is thrown away or destroyed as previously stated.

It is understood that any suitable wire and fibrous string of suitable quality may be employed in forming the hair cleaner. Also the backing of both the comb and brush can be formed of any cheap suitable material.

I claim as my invention:

1. The method of forming a hair cleaner consisting of twisting wires together to form a strand and simultaneously weaving short lengths of fibrous string into the strand so that there is a short string secured in each twist of the strand, then bending the strand to form integrally connected teeth of a comb or brush, then severing proper lengths of integrally connected teeth, and then securing the severed lengths of teeth in a backing of a comb or brush.

2. The method of forming a hair cleaner

consisting of twisting two wires together to form a strand and simultaneously weaving short lengths of fiber string into the strand so that there is a short string to each twist in the strand, then treating the strand to cause the short lengths of fiber strings to unravel to form small brushes at right angles to the strand, then bending the strand to form teeth adapted to be attached to a comb or brush.

3. In a hair cleanser the combination of a strand formed of twisted wire; a short length of fiber string secured in each twist of said strand and arranged to extend at right angles thereto, said strand being bent to form integrally connected V-shaped teeth, and a backing in which the butt ends of said teeth are secured.

In witness whereof, I have hereunto affixed my signature.

MAX H. SEEGER.
